UNITED STATES PATENT OFFICE.

JOHN C. KNIGHT, OF MERIDEN, CONNECTICUT, ASSIGNOR OF ONE-HAL
THE MERIDEN MALLEABLE IRON COMPANY, OF SAME PLACE.

EXTENSION-CHANDELIER.

SPECIFICATION forming part of Letters Patent No. 295,020, dated March 11, 1883
Application filed November 26, 1883. (No model.)

To all whom it may concern:

Be it known that I, JOHN C. KNIGHT, of Meriden, in the county of New Haven and State of Connecticut, have invented a new Improvement in Extension-Chandeliers; and I do hereby declare the following, when taken in connection with accompanying drawings and the letters of reference marked thereon, to be a full, clear, and exact description of the same, and which said drawings constitute part of this specification, and represent, in—

Figure 1, a sectional side view of so much of the fixture as will illustrate my invention; Fig. 2, a vertical section of the locking mechanism enlarged; Fig. 3, a top or plan view of the locking device; Fig. 4, a side view of the ring-shaped spring detached; Fig. 5, a modification.

This invention relates to an improvement in that class of lamp-chandeliers which are made adjustable as to elevation, and in which a telescopic rod is employed, one portion being secured to the ceiling and the lamps to the other portion, so that the movable portion may be drawn down or raised, as occasion may require. This class of fixtures is provided with a lifting device to counterbalance the weight of the movable part of the fixture, and as the weight of the movable part is variable, because of different weights of lamps or shades which may be applied, or because of the fount containing more or less oil, it is necessary that there shall be some securing device to hold the movable part at any position to which it may be adjusted.

It is to the securing device that my invention particularly relates; and it consists in the construction as hereinafter described, and more particularly recited in the claims.

A represents the inner rod or tube, and B the outer tube, to which the chandelier-arms are attached in the usual manner. The part A is fixed or secured to the ceiling. Through this tube A a cord or chain, C, extends downward from the lifting device above, and into connection with the movable part B, as at a. This lifting device above is common and well known, and does not require description in this specification; or, instead of applying the lifting device above, it may be

a helical spring extending down through tube A and into the tube B, its upper end secured to the tube A, and the lower end the movable part below, as at a, and so drawing down the movable part will extend the spring. Then the reaction of the spring will aid in lifting the movable part, the weight of the spring being supposed to substantially counterbalance the movable part of the fixture. The lifting device, however, is no part of my invention.

At or near the upper end of the tube an annular chamber or recess, D. In recess a divided elastic ring, E, is arranged around the inner tube, so as to rest on the bottom of the chamber D. Opposite the division of the ring a projection, b, extends radially and at the divided ends there is a projection respectively d e. These projections extend onto the bottom of the chamber, so as to form a bearing or support for the ring. This is of somewhat less diameter than the inner tube, and so as to closely embrace it and firmly thereon. Between the two projections d e of the divided ring, which are a little distant from each other, a cam, f, is held from which an arm, h, extends, and is preferably turned around to the side, as seen in Fig. 3. From the end of this arm h a cord, chain or wire, i, extends downward between the outer and the inner tube—say, to a transverse bar, F, in the lower end of the chandelier. This bar extends outward to the right and through a slot, and so as to be easily reached by the fingers. A person then applying fingers to the bar F and pulling down will draw down the arm h of the lever and correspondingly turn the cam f between the ends d e of the ring, as seen in broken line and such turning of the cam will open the divided end of the ring, causing the ring to expand and release its grasp upon the inner tube or rod, and when the ring is thus held the movable part may be raised or lowered, the case may be. The elasticity of the ring itself serves to return the cam and arm h when the pull from below is released and to regrasp the inner rod or tube. The cam is best held in its position by making a notch, l, in the projecting end e narrower than the cam,

Figs. 3 and 4, and then making the notch, and so as to lie therein, as shown. The elastic asps the rod so firmly that it will resist the power of the spring, or whatever device is, that power being always nt to hold the movable part up against g wherever it may be on the fixed tube

B; and while usually a smooth inner surface of the ring and a correspondingly smooth surface of the fixed tube will be sufficient, the fixed tube may be annularly ribbed, as in Fig. 5, and the inner surface of the ring correspondingly grooved, as seen in the same figure, the ribs of one interlocking with the ribs of the other; or the corresponding surfaces of the spring and the inner tube may be made otherwise irregular. This construction makes the gripping or locking mechanism independent of the lifting power, thereby overcoming difficulties in those previous constructions which require that there be a lifting movement to force an engagement between the stationary and movable

We represented the connection from the cam, which operates the cam, as being down through the tube to a cross-bar, F, below; this connection may be to any of the usual ways for operating the clamping mechanism of tension-fixtures.

In some cases it is desirable that the clamp device shall aid in supporting the movable part of the fixture. To do this the chamber is provided with a cover, G, against the upper end of the ring will bear as is upon the bottom of the chamber. This is and top of the chamber are to be understood as shoulders in the outer tube, against which the ring-shaped spring may bear. This is not for the movable part of the fixture is able in case of the giving way of the lifting device; or, as in some cases, the chamber may be a greater weight than the counterbalance can support, and therefore, if left the movable part would fall. By making the shoulder above, therefore, the ring-shaped spring grasping the inner tube serves support for the movable part of the fixture independent of the lifting device.

In very light fixtures this locking device may be employed without any lifting or counterbalancing mechanism. In that case to adjust the fixture the person pulls downward—say, the bar F—to open the grasp of the ring, then moves the fixture up or down, as the case may be, and when arrived at the desired position releases his hold and the grasp is made upon the inner tube, so as to secure the movable part in that position.

I claim—

1. The combination of the stationary inner tube or rod, A, the outer tube carrying the lamps, and constructed with a recess or shoulder, D, the divided ring-shaped spring E, surrounding the inner tube, and constructed to take a bearing upon the bottom of the shoulder or recess D, and so as to closely embrace the inner tube, the cam f between the divided ends of the spring, the said cam provided with an arm, h, extending therefrom, and a connection from the arm downward, whereby said cam may be turned to relieve its grasp upon the inner tube, substantially as described. 75

2. The combination of the inner tube or rod, A, the outer tube, B, carrying the lamps, the divided ring-shaped spring E, arranged in a recess in the outer tube, and so as to embrace the inner rod or tube and take a bearing upon the bottom or top of said recess, as the case may be, a cam, f, between the ends of said divided ring-shaped spring, said cam provided with an arm, h, and connection therefrom 85 downward, whereby said cam may be turned to release the grasp of said spring upon the inner rod, substantially as described.

3. The combination of the inner stationary tube or rod, A, the outer movable rod, B, constructed with an internal recess, D, the divided ring-shaped spring E, arranged in said recess, and constructed to grasp the inner rod, one of the ends of the divided spring constructed with a notch, l, the cam f, with its arm h, arranged in said notch l as a fulcrum, the cam standing between the divided ends of the ring-shaped spring, and a connection from the arm downward, whereby said cam may be turned, substantially as described. 90 95

JOHN C. KNIGHT.
